CLAIM

The ornamental design for a ground fault circuit interrupter, as shown and described.

DESCRIPTION

FIG. 1 is a front perspective view of a ground fault circuit interrupter according to the present invention;

FIG. 2 is a back perspective view of a ground fault circuit interrupter according to the present invention;

FIG. 3 is a front view of a ground fault circuit interrupter according to the present invention;

FIG. 4 is a back view of a ground fault circuit interrupter according to the present invention;

FIG. 5 is a first side view of a ground fault circuit interrupter according to the present invention;

FIG. 6 is a second side view of a ground fault circuit interrupter according to the present invention;

FIG. 7 is a third side view of a ground fault circuit interrupter according to the present invention; and,

FIG. 8 is a fourth side view of a ground fault circuit interrupter according to the present invention.

The broken lines shown in the drawings are for the purpose of illustrating portions of the ground fault circuit interrupter and form no part of the claimed design.

1 Claim, 5 Drawing Sheets
